John McRitchie of Philadelphia, Pennsylvania,
Sellers Island

The Schedule referred to in his Letter, dated and making part of the same now
bearing a description on the scroll, of the said John McRitchie witness
of his improvement for the machine for cutting cast-iron screws.

To all to whom these presents shall come. Be it known that John
McRitchie of the City of Philadelphia and State of Pennsylvania have
invented a new and useful machine for cutting cast-iron screws, and
that the following is a full and exact description of the construction and
operation of the said machine as invented by me.

The machine consists, first, of a square piece of iron (A.) made perfectly
level on the surface upon which a piece of steel (1) is fastened
in the middle, so worked as to receive the vice of metal (A') on
which the screw is to be cut. The remainder of the surface is taken up
by two slides (B.B') which are provided with steel rollers (C.C')
fastened upon pivots, and propelled towards each other by the cord &
weights (D). Pairs of metal properly prepared are alternately put
into the machine & turned round by a hand or other means, whilst the
rollers or revolving cutters are pressed against them until the screw is
finished. Light and left-handed screws may be cut by this principle,
of any dimensions. However the threads of the screw be very
coarse it will be necessary to begin them in the ordinary way, and
to put them into the machine to finish them.

What I claim as my undivided invention and discover-
y of the above described machine and for the use of which I wish
an exclusive privilege are the revolving cutters or dies.
